FANNIE A. B. RIGGS, OF EAST MCKEESPORT, PENNSYLVANIA.

WASHING-MACHINE.

1,156,177.

Specification of Letters Patent.

Patented Oct. 12, 1915.

Application filed July 6, 1914. Serial No. 849,195.

To all whom it may concern:

Be it known that I, EDWIN E. RIGGS, a resident of McKeesport, in the county of Allegheny and State of Pennsylvania, have 5 invented a new and useful Improvement in Washing-Machines, of which the following is a specification.

This invention relates to washing machines.

10 The object of the invention is to provide a simple and inexpensive machine which is very efficient, which is easy to manipulate, and which operates by suction or vacuum in such manner as to force through the fabric or clothes in opposite directions currents of the washing liquid, and which therefore thoroughly washes the clothes without liability of injury to the same.

20 The invention comprises the construction and arrangement of parts hereinafter described and claimed.

25 In the drawings, Figure 1 represents a side elevation of a washing machine embodying the invention; Fig. 2 is a sectional elevation thereof on the line 2—2, Fig. 1; Fig. 3 is a plan view of the machine on a smaller scale; Fig. 4 is a plan view of the lower agitator; Fig. 5 is a detail sectional view on the line 5—5, Fig. 4; and Fig. 6 is a detail sectional view of an anti-friction member.

30 The machine shown in the drawings comprises a tank or receptacle 1 which may be of any suitable character and is shown as a wooden tub of common form supported upon suitable legs 2 connected by cross braces 3 which form a frame or support for the operating mechanism. Within the tub is located an agitator, presser board or false bottom 4, which may be made of any suitable material, such as sheet metal, woven wire, wood, or expanded metal, and which is shown as a sheet metal member provided 35 with a series of radially extending beads or corrugations and reinforced by a suitable metal spider 5, the radial arms of which are bolted, riveted or screwed thereto and form supports for the rim 4^a which is formed by rolling the sheet metal around a heavy wire to strengthen the agitator. The agitator is provided with a number of spaced holes or apertures 6 through which the cleaning fluid passes. The tank or receptacle 1 may be of any suitable shape, but is shown as substantially cylindrical, and the diameter of the

agitator 4 is preferably slightly less than the internal diameter of the tub 1 so that the agitator moves easily therein. Above the agitator 4 is an upper agitator or rub board 7, which may be of the same construction as the lower agitator, but is shown as a perforated wooden board having its bottom provided with a series of baffles or rubbing members 8 which are shown as extending substantially radially and which are preferably formed integral with the material of the rub board itself.

Attached to the outside of the bottom 9 of the tank 1 is a circular plate 10 having a central opening 11 into which is threaded a pipe or tube 12 which extends upwardly into the tub and whose upper end terminates just below the rim of the tub wall. The metal spider 5 fastened to the bottom of the lower agitator 4 has connected thereto a vertically extending pipe or tube 14 which surrounds and slides upon the tube 12. Within the tube 12 is located a rod or bar 15, which is provided at its upper end with a shoulder 16 upon which rests a cap 17 threaded upon the upper end of the tube 14, said cap being secured to the rod 15 by a suitable winged nut 18. The agitator 4 is therefore securely connected to the rod 15 and may be raised and lowered in the tub by lifting or lowering the rod 15. Part of the weight of the lower agitator 4 and the clothes supported thereon is carried by a suitable spring 19 surrounding the tube 12 and resting on the floor of the tub and at its upper end engaging the lower face of the agitator 4. This is preferably a brass or galvanized metal spring which will not rust or corrode and consequently cannot injure the fabrics, all other metal parts within the tub being galvanized or of non-corroding metal, for the same reason.

40 The upper agitator 7 has a central aperture 20 of a diameter slightly larger than that of the cap 17 and nut 18 so that it can be readily slipped over the same to a position surrounding the tube 14. It is provided with a plurality, four being shown, of anti-friction members 21, shown as rollers journaled on suitable studs 22 secured at intervals to the upper surface of the agitator and in such position that they contact with the wall of the tub and prevent said agitator from tilting or becoming askew therein as the washing operation proceeds. The

upper agitator is also provided with an upright arm shown as a bar or rod 23 secured near to the periphery of the agitator, and which at its upper end is provided with a yoke 24 extending out over the rim of the tub.

The driving mechanism may be of any suitable type, either operated by hand or by power. As shown, the tub is provided with 10 a suitable bracket 25 in which is journaled a shaft 26 to one end of which is secured a lever 27, whose upper end passes between the arms of the yoke 24, and the other end of which shaft is provided with an arm 28 15 extending downwardly and connected by a link 28^a to a wrist pin 29 on a gear 30 loosely journaled on a shaft 31 carried by suitable bearings 32 secured to the underframe. Said gear meshes with a gear 33 secured to 20 rotate with a shaft 34 journaled in bearings 35 carried by the frame, and which shaft is provided with a fly wheel 40 and a crank 36 to which is connected one end of a link or connecting rod 37 whose other end is connected to the lower end of the rod 15. Preferably, the floor plate 10 is provided with 25 downwardly extending bosses or projections 38 in which are mounted antifriction members 39 shown as rollers, which bear against 30 the rod 15 and reduce the friction.

If the machine is to be operated by power a suitable driving means, such as an electric motor 41 or the like, is connected to the shaft 34, and in such case shaft 34, through the 35 gears 33 and 30 oscillates the lever 27 and, through the connecting rod 37, reciprocates the rod or bar 15. As shown, however, the machine may be operated by hand, lever 27 being the operating lever. The upper rub 40 board 7 is lifted off and the clothes are placed upon the lower agitator 4. Sufficient cleaning liquid is poured into the tub to cover the clothes therein and the rub board 7 is placed in position as shown in the drawings. Lever 27 may then be oscillated back and forth by hand and by means of the yoke 24 oscillates the rub board 7 back and forth in the tub around the tube 12. Arm 28 rotates the gear 30, which in turn rotates 45 shaft 34 and by means of the connecting rod 37 reciprocates the rod up and down, which consequently raises and lowers the agitator 4. This motion produces a suction

or vacuum in the cleaning fluid and forces the latter back and forth through the apertures in the upper and lower boards and through the clothes lying on the agitator and therefore cleanses the same thoroughly. The upper agitator or rub board 7 lies on top of the clothes and is oscillated back and forth around the vertical axis so that its baffles 8 continuously rub the clothes and stir them up. The combined action of the two boards produces a very thorough cleansing action without liability of injuring the 60 clothes.

Preferably the gearing is so adjusted that the up and down motion of the lower agitator is more rapid than the oscillation of the rub board 7. In practice the agitator 4 70 moves up and down from one and one-half to four times for each oscillation of the rub board 7, although any suitable proportion of the motions may be employed.

The machine is simple and can be readily 75 manufactured and assembled at low cost. It is easy to manipulate and permits ready insertion and removal of the clothes.

What I claim is:

1. A washing machine, comprising a stationary tank, a perforated agitator therein, a rub board lying above said agitator, and means for positively raising and lowering said agitator and oscillating said rub board.

2. A washing machine, comprising a stationary tank, a perforated agitator therein, a perforated rub board lying above said agitator, an operating member, and connections between said member and agitator for raising and lowering said agitator, and between 90 said member and rub board for oscillating the same.

3. A washing machine, comprising a stationary tank, a perforated agitator therein, a rub board lying above said agitator, means for positively raising and lowering said agitator and oscillating said rub board, and a spring for limiting downward movement of said agitator.

In testimony whereof, I have hereunto set 100 my hand.

EDWIN E. RIGGS.
